J. S. FINKE

HEEL CLAMP

Filed July 24, 1919

Fig: 2.

INVENTOR
John Steven Finke

Fig: 1.

UNITED STATES PATENT OFFICE.

JOHN STEVEN FINKE, OF ST. LOUIS, MISSOURI, ASSIGNOR TO UNITED SHOE MANUFACTURING CORPORATION, OF PATERSON, NEW JERSEY, A CORPORATION OF NEW JERSEY.

HEEL CLAMP.

Application filed July 24, 1919. Serial No. 312,879.

To all whom it may concern:

Be it known that I, JOHN S. FINKE, a citizen of the United States, residing in St. Louis, in the county of St. Louis and State of Missouri, have invented certain Improvements in Heel-Clamps, of which the following description, in connection with the accompanying drawings, is a specification, like reference characters on the drawings indicating like parts in the several figures.

This invention relates to the manufacture of shoes, and more particularly to devices for clamping heels to unfinished shoes while on their lasts prior to the operation of nailing or otherwise completing the fastening of the heels to the shoes.

An object of the invention is to provide a simple, convenient and quickly operable means whereby the unfinished shoe on the last may be supported, and a heel, to be secured thereto by a suitable adhesive, may be subjected to yielding pressure during the setting or drying of the adhesive.

In thus clamping such irregularly shaped articles as heels, there is a troublesome tendency for the article to slip, and in the use of known forms of heel-clamps this has manifested itself in the not uncommon lateral displacement of the heel when glued or cemented in place. A shoe with its heel so displaced is, of course, unsalable, so that it is necessary to remove such a heel and re-fasten it in its proper position. An object of the invention, accordingly, is so to support the heel while tightening the clamp and while the adhesive is setting that any lateral displacement of the heel with respect to the shoe will be prevented.

A further object of the invention is so to arrange the heel engaging member that it may be capable of self-adjustment to a considerable extent, in order to conform itself to various styles of heels, and to provide also positive means for adjustment to adapt the device to use with shoes having heels of different heights or on lasts of different heights.

In the illustrated embodiment of this invention there is accordingly provided a movable, preferably pivoted, member for contacting with the rear surface and sides of the heel, which, co-operating with a heel tread surface engaging member, holds the heel and by means of suitable operating

mechanism clamps it in place on the heel 55 seat of a last-supported shoe.

For purposes of illustration a preferred form of the invention is shown in the accompanying drawings. It is to be understood, however, that this form is merely an 60 example of many that might be used, and that in its broader aspects the invention is in no way limited to the specific form shown.

The foregoing and other features of the 65 invention will now be described more fully with reference to the accompanying drawings and pointed out in the claims.

In the drawings, Fig. 1 is a view partly in side elevation and partly in section of the heel clamp and its support;

Fig. 2 is a cross-section on the line 2—2 of Fig. 1.

The clamp is mounted on a standard 6 75 provided with a base 8 for attaching it to a bench or the like and carrying at its upper end a sleeve 10 in which is yieldingly supported, by means of a stiff spring 12, a plunger 14 carrying at its upper end a pin 80 16. To prevent the displacement of plunger 14 the latter is provided near its lower end with a groove 17 to engage a screw 18 threaded in the sleeve of the standard. Near its middle portion the standard is provided 85 with an approximately U-shaped slot 20 having one of its arms longer than the other for a purpose which will hereinafter be described. This slot serves as a bearing for a pin 22 which pivots one member 24 of a 90 toggle couple to the standard. The other member of the toggle couple consists of a pair of parallel rods 26 pivoted at their lower ends upon a rod 28 carried by the arms of a yoke member 24 and carrying at 95 their upper ends a heel receiving member 30. An extension 25 of toggle member 24, may conveniently be used as a toggle operating handle. Heel receiving member 30 consists of a more or less stirrup-like portion or heel cup 32 for engaging the tread face of the heel and a rearwardly extending portion 34 which encircles or embraces the rear and side portions of the heel and is provided with a contact member 36 pivoted at 100 38 for self adjustment in conformity to the contour of that portion of the heel. This contact member preferably consists of a seat

105

29 of suitable material provided at its heel engaging face with a pad 40 of felt or the like to avoid injury to the heel. The tread face engaging surface of portion 32 may be 5 similarly padded.

In the use of this clamp the lasted shoe to which a heel is to be attached is positioned with the jack pin hole of the last over the pin 16 of the clamp, the adhesive 10 is thereupon applied in the usual manner and the heel placed in position on the heel seat of the shoe. During these operations the toggle couple is in the dotted line position of Fig. 1 and in no way interferes 15 with the convenient handling of the shoe and the heel. The handle 25 of the lower toggle member is then manipulated by the operative to raise the same still further if necessary and the heel engaging member is 20 placed in position over the heel, and holds it against any undesired displacement, laterally or otherwise. Handle 25 is thereupon lowered to move the pivot rod 28 of the toggle to and slightly past its dead centre, 25 whereupon the heel is effectively clamped in place. When moved past dead center the rod 28 engages a shouldered portion of the standard 6 which limits the movement of the member 24 so as to maintain the clamping 30 pressure.

The device is well adapted to use with different sizes and styles of shoes on account of the possibility of self adjustment of the contact member for engaging the 35 rear surface of the heel. Moreover shoes mounted on lasts of different heights or with heels of different heights are easily accommodated on account of the spring support for the last pin 16 and such accommodation 40 is further permitted by the fact that the pin 22 may be moved as may be necessary from time to time from the longer to the shorter of the U-shaped slots 20 and vice versa which has the effect, of course, of 45 somewhat raising or lowering the position of the heel engaging member.

Having described my invention, what I claim as new and desire to secure by Letters Patent of the United States is:

50 1. A clamping device comprising, in combination, means to apply pressure to the heel seat portion of a shoe, and a heel engaging member adapted to receive the heel of a shoe and exert pressure upon the tread face of the heel and upon an area extending from the breast at one side of the heel around the curved rear portion to the breast at the other side of the heel and including that portion of the sides and rear of the heel which lies adjacent to the seat.

55 2. A clamping device comprising a last support, heel engaging means comprising members for engaging spaced localities on the rear and tread surfaces of a heel, means for connecting said members together con-

60 structed and arranged to permit variation of their relative angular positions according to the style of the heel, and means yieldingly to clamp a heel held by the heel engaging means against the heel seat of a shoe on a 70 last mounted on the support.

3. A clamping device comprising a last support, a heel engaging device comprising a member for engaging the tread face of a heel and a contact member mounted thereon 75 with provision for tilting adjustment relatively to the tread-engaging member for engaging the rear surface of the heel, and means relatively to move said device with respect to said support to clamp a heel held by the heel engaging means against the heel seat of a shoe on a last mounted on the support, said means being constructed and arranged to effect relative swinging movement between said support and said heel 80 engaging device in a direction longitudinally of the shoe on unclamping to facilitate removal of the work.

4. A clamping device comprising a standard, a last support carried by the standard and mounted to yield relatively thereto during the clamping of a heel, a heel engaging member, and a toggle couple connected to the standard and the heel engaging member to clamp a heel held by the heel engaging member against the heel seat of a shoe on a 95 last mounted on the last support.

5. A clamping device comprising a standard, a last support carried by the standard and mounted to yield relatively thereto during the clamping of a heel, a heel engaging member, and a toggle couple connected to the standard and the heel engaging member, one of the toggle members being provided with a toggle operating handle 100 to clamp a heel held by the heel engaging member against the heel seat of a shoe on a last mounted on the last support.

6. A clamping device comprising a standard, a last support carried by the standard, the standard being provided with a substantially U-shaped slot having the arms of the U of unequal length, a heel engaging member and a toggle couple having one of its members connected through a pin to the U-shaped slot and its other member connected to the heel engaging member to clamp a heel held by the heel engaging member against the heel seat of a shoe on the last 115 mounted on the last support.

7. A clamping device comprising a standard, a last support carried by the standard, the standard being provided with a substantially U-shaped slot having the arms of the U of unequal length, a heel engaging member, and a toggle couple having one of its members connected through a pin to the U-shaped slot and its other member, and consisting of a pair of rods connected to the 125

- opposite sides of the heel engaging member to clamp a heel held by the heel engaging member against the heel seat of a shoe on the last mounted on the last support.
- 5 8. A clamp comprising, in combination, a heel supporting device having part to engage the tread surface of a Louis heel and another part mounted with provision for tilting adjustment relatively to the first 10 part to engage the surface of the backwardly projecting top portion of the heel, a device to engage a last in a shoe to be clamped to the heel, one of said devices being stationary, and a pair of links engaging 15 the other device to swing it backwardly out of the way when the clamp is opened.
9. A clamping device having a portion for engaging the tread face of a heel, and a portion shaped to conform to the rear portion 20 of the heel, said last named portion having pivoted thereto a contact member for engaging the rear surface of the heel.
10. A clamping device having a heel engaging member provided with a stirrup-like 25 portion for engaging the tread face of the heel and a rearwardly extending portion to which is pivoted a contact member shaped to conform to and for engaging the rear surface of the heel.
- 30 11. A clamping device having a heel engaging member provided with a stirrup-like portion for engaging the tread face of the heel, and a rearwardly extending portion to which is movably attached for self-adjustment 35 a member shaped to conform to and for engaging the rear surface of the heel.
12. A heel clamp comprising, in combination, a support for a shoe to which a heel is to be attached, a head to engage the tread 40 surface and the rear surface of a heel thereon, a pullrod carrying said head mounted adjacent to the support, and a manually operable lever to pull said rod and hold it in position to clamp the head against the 45 heel while adhesive between the heel and the shoe is drying.
13. A heel clamp comprising, in combination, a support for a shoe to which a Louis heel is to be attached, spaced rods mounted 50 one on each side of the support, and a head carried by said rods and movable to clamp a heel to the shoe, said head having a portion to engage the tread surface of the heel and another portion angularly adjustable 55 relatively to the first portion to engage the projecting rear surface of the heel, and said rods being movable to carry the head to and from clamping position.
14. A clamping device comprising a last 60 support, a heel engaging head provided with a heel tread face engaging portion and a member pivotally connected with said head for self-adjustment into position to embrace the rear portion of the heel, and a 65 pivotally mounted device relatively to move the support and said member to clamp a heel held by the heel engaging head against the heel seat of a shoe on a last mounted on the support and to effect relative movement between said heel engaging head and said support in a direction longitudinally of the shoe.
15. A clamping device comprising a last support, heel-engaging means provided with a surface to engage the tread face of a Louis heel on a shoe on a last supported thereby to prevent it from slipping forward and with a surface to engage the sloping rear side of the heel to prevent it from slipping rearwardly and from tipping, and means relatively and yieldingly to move said support and means in a direction substantially normal to the heel seat surface of the shoe and at an acute angle to both heel engaging surfaces, to clamp the last and shoe and heel together.
16. A clamping device comprising a last engaging member, heel engaging means having a contact member for engaging the rear and side surfaces of a heel, and means including links on opposite sides of one member and a connection between the links and the other member allowing it to tilt about an axis transversely of the shoe to apply to the heel pressure in a direction normal to the heel seat of a shoe on a last mounted on said last support, to clamp the heel in position on the shoe.
17. A clamping device comprising a last engaging device, a heel-engaging device 100 comprising pivotally connected members formed and arranged to contact respectively with the rear and lateral surfaces of a heel and with the tread surface of the heel to prevent slipping of the heel from its desired position on the heel seat of a shoe on a last mounted on the last support and arranged to vary their relative inclinations according to the shape of the heel, and means including a pivotally-mounted member to apply a clamping pressure to said heel in a direction normal to the heel seat of the shoe and relatively to swing said devices to facilitate removal of the work.
18. A clamping device comprising a shoe support, a heel cup having a portion for engaging the tread face of the heel of a shoe mounted on said support and a member pivotally mounted within the heel cup for self-adjustment into position for engagement with the rear surface of heels of different styles, and means to move the heel cup toward the shoe support to clamp a heel held thereby against the heel seat of said shoe and to swing the heel cup about the shoe support to and from active position.
19. A clamp comprising, in combination, a last-engaging device, a heel-engaging device including members to engage the tread and rear surfaces of a heel, and links piv-

totally connected to one of said devices and pivotally mounted to swing about the other device.

20. A clamping device comprising, in combination, a shoe support, spaced rods arranged one on each side of said support, a heel engaging head connecting the upper ends of said rods, said head being constructed and arranged to apply pressure to the tread face and to the rear surface adjacent to the heel seat of a Louis heel, a member connecting the lower ends of said rods and arranged to operate them to apply pressure to said head to clamp a heel on a shoe on the support, and means for co-operating with said member to maintain the clamping pressure.

21. A clamping device comprising, in combination, a work support, a clamping member, and a toggle pivotally connected at opposite ends to said support and said member, one of said pivotal connections consisting of a pin working in a U-shaped slot having arms of unequal length, to vary the throw of the toggle as described.

22. A heel clamp comprising, in combination, a last engaging support, a support having spaced surfaces to engage the side and tread surfaces of a heel to be clamped

against a shoe on a last engaged by the first support, a pair of links attached to one of the supports and arranged to straddle the last and shoe, and a manually operable member to pull on the links to move the support attached thereto toward the other support to clamp the heel and the shoe together.

23. A clamp as defined by claim 22, in combination with a spring arranged to co-operate in the clamping action so that the heel and the shoe are yieldingly held together.

24. A heel clamp comprising, in combination, a member to engage a last in a shoe, a support having spaced portions to engage the tread and lateral surfaces of a Louis heel to be clamped against the shoe, a manually operable lever to impart relative bodily motion to said member and the support to clamp the heel and the shoe together, and a spring arranged to allow for lost motion of the lever to provide for heels of varying height and to provide for effecting the clamping under yielding tension.

In testimony whereof I have signed my name to this specification.

JOHN STEVEN FINKE.
